UNITED STATES PATENT OFFICE.

ERNEST W. GAUBE, OF CLEVELAND, OHIO.

DESIGN FOR A JUG.

40,815.

Specification for Design.

Patented Aug. 9, 1910.

Application filed June 13, 1910. Serial No. 566,703. Term of patent 7 years.

To all whom it may concern:

Be it known that I, ERNEST W. GAUBE, a citizen of the United States, residing at Cleveland, in the county of Cuyahoga and State of Ohio, have invented a new, original, and ornamental Design for Jugs, of which the following is a specification, reference being had to the accompanying drawing, forming part hereof.

showing my new design, and Fig. 2 is a side elevation of said jug, the view being taken at right angles to Fig. 1.

I claim:

The ornamental design for a jug, as shown.

ERNEST W. GAUBE.
